UNITED STATES PATENT OFFICE.

SAMUEL K. WHITE, OF CHICAGO, ILLINOIS.

CLUTCH MECHANISM.

SPECIFICATION forming part of Letters Patent No. 447,019, dated February 24, 1891.

Application filed June 28, 1890. Serial No. 357,138. (No model.)

To all whom it may concern:

Be it known that I, SAMUEL K. WHITE, of Chicago, in the county of Cook and State of Illinois, have invented certain new and useful Improvements in Clutch Mechanism; and I do hereby declare that the following is a full, clear, and exact description thereof, reference being had to the accompanying drawings, and to the letters of reference marked thereon, which form a part of this specification.

This invention relates to a novel construction in clutches for communicating rotary motion from one revolving part to another.

The invention consists in the features of construction and combinations of parts hereinafter fully described, and pointed out in the appended claims.

In the accompanying drawings, Figure 1 is a view in side elevation of an apparatus embodying a preferred form of my invention. Fig. 2 is a front elevation of the same. Fig. 3 is a central vertical longitudinal sectional view of the device taken on line 3 3 of Fig. 2. Fig. 4 is a view in cross-section taken on the line 4 4 of Fig. 3. Fig. 5 is a top plan view of the device with the driving-pulleys shown in section. Fig. 6 is a central vertical longitudinal sectional view of a modified form of construction embodying my invention, taken on the line 6 6 of Fig. 7. Fig. 7 is a view of the same in cross-section on the line 7 7 of Fig. 6. Fig. 8 is a central vertical longitudinal sectional view of another modified form of construction embodying my invention. Fig. 9 is a view of the same in cross-section on the line 9 9 of Fig. 8.

In said drawings, Figs. 1 to 5, both inclusive, A represents as a whole the support or frame of the apparatus, which comprises a bed-plate a and an overhanging arm A' , which is provided with a cylindric aperture a' , extending longitudinally through the same and forming a journal-bearing. The outer part of said overhanging arm A' is cylindric and forms a bearing A^2 for the driving-pulleys B B' B^2 , which are arranged in similar manner as the ordinary belt-pulleys, the bearing A^2 being eccentric with the bearing-aperture a' . The said pulleys are conveniently formed integral with a hub B^3 , which is provided with a bearing-aperture fitting the bearing A^2 . The said pulleys are held in place upon said overhanging arm by an annular plate A^3 , which is secured to the for-

ward end of the arm A' conveniently by 55 means of screws a^3 a^2 . The said annular plate A^3 has a diameter somewhat greater than that of the overhanging arm A' , so that it extends outside of the same and overlaps, Figs. 3 and 5, the front face of the hub B^3 . 60 The main portion of the hub preferably extends outward past the end of the supporting-arm a distance equal to the thickness of the annular plate A^3 , and the outer marginal edge of said plate A^3 rests in an annular 65 groove b , formed in the hub at the inner marginal edge, so that the outer faces of the hub and plate are flush with each other.

C indicates the driven shaft of the apparatus, which is supported in the journal-bearing a' , formed in the frame. The said shaft C may be connected in any suitable way with the parts to be driven, but is herein shown as provided with a wheel or disk C' , which may be a crank-disk. The said shaft C is held from endwise movement within the journal-bearing by means of a transverse pin c , located in the frame and engaging a groove c' in the shaft C. The forward end of the said shaft C is preferably made flush with the front 80 face of the pulley B' and the plate A^3 .

The devices for connecting the hub B^3 with the shaft C to be driven are constructed as follows:

D indicates a spring-actuated detent pivoted upon the front face of the hub B^3 by means of a pivot d , with which one end of the detent is engaged. A spring d' is secured to the said detent D, and is arranged to bear against the inner face of the pulley B^2 and 90 adapted to throw the detent D inwardly. A stop-pin d^2 is located in the hub in position to engage the said detent D and limit the inward movement thereof. The said detent D is provided with a notch or recess d^3 , formed 95 in the inner face thereof.

The shaft C is provided with a slot C^2 , extending a considerable distance inwardly from one side thereof and opening through the end of the shaft nearest the outer face of 100 the pulley-hub. Within said slot is located a swinging dog E, which is mounted on a pivot e , extending transversely through the slot C^2 near the inner or rear end of the latter. The dog E projects from the slot at the 105 end of the shaft and is provided with an arm E' , adapted for engagement with the notch d^3 of the detent D. The dog E is held nor-

mally in position free from the detent by means of a spring e' , suitably applied for this purpose, the said spring being herein shown as made of leaf form and as interposed 5 between the edge of the dog and the said inner wall of the slot and as attached to the dog, so as to bear at its free end against the said wall of the slot. The said spring may, however, be arranged otherwise in practice, 10 as found convenient or desirable.

A slot or recess a^3 is formed in the arm A' in a plane at right angles to the pivot-pin e of the dog E , and in position to receive the outer part or end of the said dog when the 15 free end of the latter is thrown by the spring e' away from the detent D . The plate A^3 , which holds the pulley-hub in place, is notched or cut away opposite the recess a^3 , as indicated at a^4 , Fig. 2, to admit the end of the 20 dog into the said recess.

The pin d^2 , by which the detent D is held from inward movement, is located so far from the center of motion of the pulley-hub as to be free from contact with the arm E' of the 25 dog E when said dog is swung about its pivot out of the notch a^3 . The part of said detent containing the notch d^3 is located in position for engagement with the said arm E' of the dog when the dog is swung out of the notch 30 a^3 and the detent is in contact with the stoppin d^2 , against which it is held by the spring d' . The edges of the detent at either side of the notch d^3 therein are, however, beveled or inclined outwardly from the notch, so that 35 the contact of the arm of the dog with the said detent, when said dog is thrown laterally out of the notch a^3 and the pulleys are revolved, will operate to force the detent outwardly against the action of the spring d' , 40 and thus allow the arm E' of the dog to enter the said notch d^3 of the detent.

F , Figs. 3, 4, and 5, indicates a sliding rod or bar which is located and adapted to slide longitudinally within a groove a^8 , formed in 45 the outer surface of the supporting-arm A' and opening into the inner end of the recess a^3 . As shown by Figs. 3 and 5, the said groove a^8 is of less width than the said recess a^3 . The said sliding rod F fits closely within 50 the said groove and has its outer face flush with the outer cylindric surface of the arm A' . An enlargement or head f is formed upon the forward end of the said rod F and fits within the recess a^3 . The said head f has its 55 end surface beveled, as shown at f' , and adapted to engage a correspondingly-beveled surface or shoulder e^2 of the dog E . The parts are so arranged that when the said head f is at the inner end of the recess a^3 the outer 60 end of the dog, which is held in contact therewith by the spring e' , will be disengaged from the detent D . The said head and the beveled surface of the dog are so arranged, furthermore, that when the head is thrust into 65 the outer end of said recess the dog will be swung laterally against the action of the spring, and the end of its arm E' thereby

brought into position to engage the said detent. The longitudinal slot a^8 and rod F therein extend to a point outside of the pulley-hub, and the rod is provided at its inner or rear end with an outwardly-extending lug or pin f^2 . The frame A is provided with a transverse guide-recess a^6 , Figs. 1 and 3, having parallel walls $a^7 a^7$, between which is located a sliding cam-plate G , provided with an actuating-rod g . The pin f^2 on the sliding bar projects into the said recess a^6 and is engaged by an inclined or cam slot f^3 , formed in the said cam-plate G . Said cam-plate is 70 held in place by means of a plate f^4 , which is secured to the frame A by screws in the manner shown, Figs. 1, 3, and 5. The said cam-plate may be shifted by power applied to the rod g , so as to move endwise the rod 75 F by the action of the pin f^2 in the oblique slot of the said plate, in an obvious manner.

The parts being constructed and arranged as described, the operation is as follows: Assuming the parts to be in the position shown 80 in the drawings—that is to say, with the driving-pulleys and shaft disconnected and the said driving-pulleys running loose upon the supporting-arm of the device—the outer end of the dog E will at this time stand within the 85 slot a^3 in said supporting-arm. When it is desired to cause the shaft and parts connected therewith to rotate, the cam-plate G is moved so as to thrust the sliding rod F forwardly, the inclined face f' of the head f on the said 90 rod bearing against the incline e^2 of the dog E , thereby swinging the said dog upon its pivot against the action of the spring, so that the end of the dog is thrown out of the notch a^3 and the end of the arm E' of said dog is 95 brought into the path of the detent D upon the front face of the pulley-hub. As the free end of the detent approaches the arm of the dog in the turning of the hub, the inclined edge of the said detent at the side of the notch 100 therein will engage the end of the arm, so that said detent will be depressed or thrown outwardly upon its pivot until the notch d^3 on the inner edge of said detent arrives opposite the end of the arm of the dog, whereupon 105 the said detent will be thrown inwardly under the influence of the spring, and the said notch d^3 will engage the end of the arm, so that the driving pulley and shaft will be 110 locked together. It will be noted that as 115 soon as the shaft is turned a little distance the dog will be carried away from the slot a^3 and the head f of the rod, by which it was thrown out of said slot, and bears against the inner edge of the circular plate A^3 as the parts 120 revolve, said plate serving to keep the said dog in engagement with the detent on the driving-pulleys. After the parts are thus connected and the dog has been carried away 125 from the slot a^3 , as described, the cam-plate 130 can be thrown to the opposite limit of its movement, and thus withdraw the head f of the rod F to the rearward limit of its movement. When the parts are thrown in this

position, the shaft C will be prevented from making more than one revolution with the driving-pulleys, for the reason that at the completion of one revolution of the parts the 5 dog will enter the slot a^3 in the supporting-arm under the influence of the spring which actuates it and at the same time become disengaged from the detent upon the driving-pulley. The engagement of said dog 10 with the slot a^3 will positively hold the said shaft from turning until the rod F is again actuated to release the dog from the said slot a^3 .

It is obvious that the driving and driven 15 parts can be made to rotate together for any number of revolutions by keeping the head f upon the sliding rod at the forward limit of its movement, so that it will close or fill the forward or outer end of the slot a^3 , and therefore 20 by form with the periphery of the ring or securing-plate A³ a continuous annular bearing-surface to hold the dog engaged with the detent D. It is manifest that when it is desired to disconnect the parts the head f may 25 be retracted, and the dog will then enter the slot a^3 when it next reaches the same in its revolution in an obvious manner. It will thus be seen that the shaft can be caused to make one or more revolutions at intervals, as 30 desired, and, furthermore, that the said shaft will always be arrested at the same point in its revolution. It will of course be seen that the notch a^3 may be placed at any angular position desired upon the arm A', according 35 to the particular point in its rotation that it is desired the shaft should be arrested and held—that is to say, the said notch is herein shown as arranged at the top of the arm A' of the supporting frame or casting; but the 40 same result will be obtained when the said notch is placed at the lower part or at one side of said arm, or at any other intermediate angular position.

A clutch made as above described is of especial advantage for use upon all machines 45 where it is desired that the machine should be stopped in every instance with its working parts in the same position—as, for instance, on a paging or numbering machine, 50 where the machine should be stopped with the type-carrying head elevated or away from the work.

A clutch of the character herein shown obviously places a machine of this kind entirely 55 under the control of the operator, while insuring the positive stoppage of the machine at a desired point automatically and without any attention on the part of the operator to secure this end—that is to say, the operator 60 may, by holding the rod F at the outward limit of its movement, retain the dog E engaged with the detent D during any number of revolutions desired; but by the shifting of said rod at any time the driven shaft will be 65 arrested and locked from further movement when the said shaft completes its revolution.

The figures of the drawings above described

show a preferred embodiment of my invention; but the main features thereof may be carried out in practice by the use of devices 70 differing in mechanical form and arrangement from the particular ones illustrated—as, for instance, some of the different forms of apparatus containing the same principles of construction and operation are shown in 75 Figs. 6, 7, 8, and 9, which will now be described.

Referring to Figs. 6 and 7 of the drawings, H indicates the base or support for the driving-shaft of the apparatus, which base is provided with a cylindric aperture h, extending longitudinally through the same and forming a journal-bearing for the driving-shaft I. The said driving-shaft I may be connected in any suitable manner with the devices 80 furnishing the power. The said shaft I is held from endwise movement within the journal-bearing by means of a transverse pin i, located in the frame and engaging a groove i' in the shaft I. The said base or support H is provided at its end adjacent to that end of the driving-shaft remote from the power devices, with a cylindric head or disk H', provided with a laterally-projecting annular flange H², concentric with the said journal-bearing h. The said flange H² is provided 85 with a recess or notch h', in which is located a sliding part or plunger h². The said plunger h² fits nicely within the notch or recess, and its face is made on the same curve as the inner wall of the flange H², so that when the plunger stands in the inner end of said recess h' it will form a continuous unbroken 90 surface.

K indicates the base or support for the driven shaft of the apparatus, which is located end to end with the support H, and is provided with a cylindric aperture k, extending longitudinally through the same, which is located concentrically with the aperture h in the support H. The said aperture k forms a journal-bearing for the driven shaft L. The said driven shaft L may be connected in any suitable way with the parts to be driven. A disk L' is secured to the said shaft L adjacent to the disk H'. The said driven shaft is held from endwise movement within the journal-bearing k by means of the said disk bearing against one end of said support K and a collar l, rigidly secured to said shaft adjacent to the other end of said support. The inner ends of the driving and driven shafts I and L are preferably made flush, respectively, with the front faces of the stationary head H' and the disk L'. 110

The devices for connecting the driving and driven shafts together are constructed as follows: The said shaft I is provided in its end adjacent to the driven shaft with a slot I', extending a considerable distance inwardly 115 from one side thereof and opening through the end surface of the shaft. Within said slot is located a swinging dog I², which is mounted on a pivot i², extending transversely 120

through the slot I' near the inner or rear end of the latter. The dog I^2 projects from the slot at the end of the shaft and is provided with an arm I^3 , conveniently arranged at 5 right angles thereto and located within the space inclosed by the flange H^2 . The said dog I^2 is movably held against the rear wall of the slot I' by means of a spring i^3 , suitably applied for this purpose, the said spring 10 being herein shown as made of leaf form and as secured at one end to the dog I^2 , near the outer end thereof, and bearing at its other end against a transverse pin i^4 in the rear portion of the slot I' . The head H' and the 15 disk L' are of about the same diameter, and the edge of the flange H^2 on said head is located adjacent to the front face of the said disk L' .

L^2 indicates a spring-actuated detent pivoted upon the front face of the disk L' by means of a pivot l' , with which one end of the detent is engaged. A spring l^2 is secured to the said detent L^2 , and is arranged to bear against a stop-pin l^3 upon the disk and serves 25 to throw the said detent outwardly. The said detent L^2 , is provided on its outer side with a lug or projection l^4 and in its inner face with a notch or recess l^5 . The said lug or projection l^4 is adapted to enter the recess 30 h' of the stationary head when the plunger h^2 is retracted, and when in this position it is obvious that the driven shaft will be held from rotation. When the said detent is thus thrown outwardly by the spring and the lug 35 l^4 stands in the slot, said detent will be out of the path of the arm I^3 of the swinging dog i^2 , carried by the driving-shaft I . When, however, the plunger is moved into the open end of the recess h' , thereby throwing the detent 40 inwardly and carrying the lug out of said recess, said detent and the notch l^5 in the inner face thereof will be located in the path of the arm I^3 of the swinging dog, which will engage the said notch in an obvious manner when it 45 arrives opposite the same. The driving and driven shafts then rotate together and the lug l^4 on said detent L^2 bears against the inner face of the flange H^2 . It is obvious that when the plunger is retracted the lug l^4 on the 50 detent will enter the recess h' when it arrives opposite said recess, and thus disconnect the shafts.

In the construction shown in the foregoing figures it is obvious that when the driving 55 and driven members of the clutch are united and are rotating together either the swinging dog E , of the form shown in Figs. 1 to 5, or the pivoted detent L^2 , of the form shown in Figs. 6 and 7, will bear and rub against a 60 stationary part of the clutch mechanism, and thereby create some, although not usually an objectionable, degree of friction. In Figs. 8 and 9 is shown a form of construction in which this frictional contact of the dog or detent is 65 obviated. In this construction the parts entering into the clutch are in the main fea-

tures similar to those shown in Figs. 1 to 5, the differences consisting, essentially, in the construction of the driven shaft and the parts for connecting the same with the driving-shaft. The said driven shaft (indicated by M) is supported in the journal-bearing a' in the frame. The said frame is not provided with any longitudinal slot a^3 , in which the sliding rod to operate the swinging dog rests, 70 nor is there any transverse guide-recess for the cam-plate. The said shaft may be connected in any suitable way with the parts to be driven, but is herein shown as provided with a gear-pinion M' . The said shaft M is 80 provided with a slot M^2 , extending a considerable distance inwardly from one side thereof and opening through the end of the shaft nearest the outer face of the pulley-hub, as in said Figs. 1 to 5. At the end of the shaft M 85 the said slot M^2 extends entirely through the same, as shown at m . Within said slot is located a swinging dog N , which is mounted on a pivot n , extending transversely through the slot M^2 in the rear portion of the latter. The 90 dog N projects from the slot at the end of the shaft, and is provided with an arm N' , adapted for engagement with the notch d^3 of the detent D , as described. The said arm N' , however, is located with relation to the slot 95 M^2 in a reverse position to that in which the arm E' of the dog E is located—that is to say, said arm N' is located at the open side of the slot. The dog N is held normally in position free from the detent by means of a spring n' , 100 suitably applied for the purpose, said spring being herein shown as made of leaf form, connected at one end to said dog N and bearing near its other end against a transverse pin m' , located in said slot M^2 . The said spring 105 n' acts upon the said dog to throw the latter away from the detent D when the latter stands near the arm of said dog. The frame A' is provided, as before described, with the slot or recess a^3 , adapted to receive the outer part 110 or end of the dog N when the latter is thrown by the spring n' away from the detent. In entering said slot a^3 it is obvious that the said dog passes through the slotted portion m of the said shaft M .

The devices for throwing the said dog toward the detent are constructed as follows: The said shaft M is provided with a central longitudinal aperture m^2 , extending from the end of the slot M^2 through the end of said shaft, said shaft being extended a considerable distance beyond the end of the frame A . Within the said aperture m^2 is located a sliding rod O , which extends into the slot M^2 , and is there provided with an offset portion 120 O' , which rests and slides against the rear wall of the slot M^2 and extends forward to a point near the front end of the same. The end of the said offset portion O' bears against a beveled surface or shoulder n^2 of the dog N . 125 The parts are so arranged that when the sliding bar stands at the forward limit of its 130

movement the offset portion of the rod will act upon the beveled shoulder n^2 of the dog and throw said dog against the action of the spring, so that the arm N' will stand in the 5 path of the revolving detent and engage the same in an obvious manner. Furthermore, when the sliding rod is retracted the spring will throw the end of the dog into the slot or recess a^3 and disengage it from the detent D .

10 The shaft M is provided in the rear of the gear-pinion M' with a transverse slot m^3 , passing through the aperture m^2 . A pin o , secured to the sliding rod, is located in said slot and extends beyond the sides of the shaft, 15 and its ends are fastened to a sliding sleeve or collar O^2 on said shaft, said collar being provided with an annular groove or channel o' . O^3 is an operating-lever pivoted to a support or bracket o^3 and provided with a forked 20 end, the arms o^4 of which are engaged with the groove o' of said collar. It is obvious that as the said lever is swung on its pivot the collar will be moved longitudinally on the shaft, which movement will move the sliding 25 rod O and offset O' in an obvious manner. It will thus be seen that as the offset O' , which bears against the dog, turns with the said dog and shaft any frictional contact of such revolving part with the stationary part is 30 avoided.

I claim as my invention—

1. A clutch comprising driving and driven members, movable parts upon said driving and driven members adapted to automatically interlock with each other, and means for moving one of said parts to disengage it from the other part, substantially as described.

2. A clutch comprising driving and driven members, movable parts upon said driving and driven members adapted to automatically interlock with each other, a stationary annular bearing-surface located in position to hold one of said parts interlocked with the other part, said annular surface being provided with a notch allowing the movement of the part which engages the same in a direction to disengage it from the other part, and a movable part acting on the said part which acts against said annular surface to hold it 50 out of said notch, substantially as described.

3. A clutch comprising driving and driven members, spring - actuated parts upon said driving and driven members adapted to interlock with each other, a stationary annular surface against which one of said parts bears, said annular surface being provided with a notch or recess adapted to allow the movement of said part which bears on said annular surface in a direction to disengage it from 55 the other part, and a movable block constructed to fill said notch, substantially as described.

4. A clutch comprising driving and driven members, interlocking spring-actuated parts upon said driving and driven members, and a movable part engaging one of said spring-actuated parts to move it into the path of the

other spring-actuated part, substantially as described.

5. A clutch comprising driving and driven 70 members, spring - actuated parts upon said driving and driven members, one of said parts being located in the path of the other and provided with a notch adapted to engage said other part and an inclined surface adjacent 75 to the notch, and a movable part acting upon one of said spring-actuated parts for disengaging it from the other spring-actuated part, substantially as described.

6. A clutch comprising a stationary part 80 having a bearing-aperture and a slot in one side of said bearing - aperture, driving and driven members mounted upon said stationary part, one of said members being slotted, a spring-actuated dog pivoted in the slot in 85 said member and having a laterally-projecting arm outside of said slot, said dog being adapted to enter the slot in said stationary part, a spring-actuated detent on the other clutch member, located in the path of the said 90 arm, and a movable part acting upon said dog for moving it into the path of said detent, substantially as described.

7. A clutch comprising a stationary part 95 having a bearing-aperture, a slot in one side of said bearing-aperture, driving and driven members upon said stationary part, a spring-actuated dog on one of said members adapted to enter said slot and to engage the other member when disengaged therefrom, a groove 100 in said stationary part communicating with said slot, and a sliding rod located in said groove and bearing at one end against said dog, substantially as described.

8. A clutch comprising a stationary part 105 having a bearing-aperture, a slot in one side of said bearing-aperture, driving and driven members upon said stationary part, a spring-actuated dog on one of said members, said dog being provided with an inclined or cam 110 surface adapted to enter said slot and to engage the other member when disengaged therefrom, a groove in said stationary part communicating with said slot, and a sliding rod 115 located in said groove and bearing at one end against the inclined surface upon said dog, substantially as described.

9. A clutch comprising a stationary part, driving and driven members upon said stationary part, spring-actuated parts upon said 120 driving and driven members adapted to interlock with each other, a sliding rod in engagement with one of said spring-actuated parts, a pin on said rod, and a cam-plate engaged with and actuating said pin, substantially 125 as described.

In testimony that I claim the foregoing as my invention I affix my signature in presence of two witnesses.

SAMUEL K. WHITE.
